UNITED STATES PATENT OFFICE

126,438

DESIGN FOR A STEAM GENERATING SADIRON

Russell I. Huffman, Dover, Ohio, assignor to
Knapp-Monarch Company, St. Louis, Mo., a
corporation of Missouri

Application February 3, 1941, Serial No. 98,711

Term of patent 7 years

To all whom it may concern:

Be it known that I, Russell I. Huffman, a citizen of the United States and a resident of Dover, in the county of Tuscarawas and State of Ohio, have invented a new, original, and ornamental Design for a Steam Generating Sadiron, of which the following is a specification, reference being had to the accompanying drawing forming a part thereof.

Figure 1 is a perspective view of a steam generating sadiron showing my new design.

Figure 2 is a side elevational view thereof, and
Figure 3 is a rear elevational view thereof.

I claim:

The ornamental design for a steam generating
sadiron, substantially as shown.

RUSSELL I. HUFFMAN.
